Primary Examiner — John Windmuller*(74) Attorney, Agent, or Firm* — Knobbe Martens Olson & Bear LLP(57) **CLAIM**

The ornamental design for an umbrella runner, as shown and described.

DESCRIPTION

FIG. 1 is a front view of an umbrella runner showing my design. FIG. 1 shows the umbrella runner disposed on an umbrella frame, where the umbrella frame is not part of the design but rather is a non-limiting environment in which the new design can be used;

FIG. 2 is a top perspective view of the umbrella runner of FIG. 1;

FIG. 3 is a bottom perspective view of the umbrella runner of FIG. 2;

FIG. 4 is a rear view of the umbrella runner of FIG. 2;

FIG. 5 is a front view of the umbrella runner of FIG. 2;

FIG. 6 is a left side view of the umbrella runner of FIG. 2;

FIG. 7 is a right side view of the umbrella runner of FIG. 2;

FIG. 8 is a bottom view of the umbrella runner of FIG. 2; and,

FIG. 9 is a top view of the umbrella runner of FIG. 2. The broken line in the figure depict an umbrella and portions of the umbrella runner that forms no part of the claimed design.

The unshaded interior areas are not part of the claimed design.
